[57] CLAIM

The ornamental design for an organizer for lipsticks and similar articles, as shown and described.

DESCRIPTION

FIG. 1 is a perspective view of an organizer for lipsticks and similar articles showing my new design;

FIG. 2 is a top plan view thereof;

FIG. 3 is a front elevational view thereof;

FIG. 4 is a bottom elevational view thereof;

FIG. 5 is a rear elevational view thereof;

FIG. 6 is a left side elevational view thereof;

FIG. 7 is a right side elevational view thereof; and

FIG. 8 is a sectional view thereof, as taken along lines
8—8 of FIG. 2.
